UNITED STATES PATENT OFFICE.

WILLIAM C. BURROWS, OF PROVIDENCE, RHODE ISLAND.

VALVE-SPRING COMPRESSOR.

Application filed September 4, 1923. Serial No. 660,822.

To all whom it may concern:

Be it known that I, WILLIAM C. BURROWS, a citizen of the United States, residing at Providence, in the county of Providence and State of Rhode Island, have invented certain new and useful Improvements in Valve-Spring Compressors, of which the following is a specification.

This invention relates to improvements in the construction of valve spring compressor employed more particularly to facilitate the removal of motor valves; and the object of this invention is to provide simple and practical construction for such a lifter which is strong and durable and which is susceptible of quick operation to be readily placed in operative position on an engine or motor and quickly operated to compress the valve spring and to be locked in spring compressed position.

A further object of the invention is to so construct the device that it may be readily adjusted to operate upon machines of different sizes and designs.

The invention further consists in the provision of an automatic lock for retaining the parts in adjusted position, the operating handle of the lock being arranged to extend into proximity with the operating lever, whereby the hand which operates the lever to compress the spring may also serve to release the lock and permit the return of the presser member back to spring release position.

With these and other objects in view, the invention consists of certain novel features of construction, as will be more fully described, and particularly pointed out in the appended claims.

In the accompanying drawings:

Figure 1 is a side elevation partly in section of my improved valve spring compressor.

Figure 2 is a top view of the device.

Figure 3 is a plan view of the presser foot removed from the frame.

Figure 4 is a sectional elevation of the hub to which the operating lever is connected.

Figure 5 is a front view of the spring latch removed.

Figure 6 is a front view of the fork in which the reel or pulley is rotatably mounted.

Figure 7 is a detailed perspective view of the pivoted lock yoke.

Figure 8 is a top view showing the lock yoke in position to engage the lock pin.

Figure 9 is a side elevation showing the lock yoke in operative position.

With reference to the drawings, 10 designates the frame portion of this device, which is preferably formed of a metal rod threaded as at 11 at its upper end. Its lower portion 12 is offset inwardly and its extremity is threaded and screwed into the T-shaped fitting 14.

The presser foot-plate 15 is provided with a threaded shank 16 which is screwed into the horizontal portion of the T-fitting 14 and bound in adjusted position by the nut 13, by which construction the frame may be laterally adjusted to fit any type of motor to which the device may be applied. The outer end of this presser foot plate is forked as at 17 to straddle the valve stem 18 and extend in under the valve spring 19.

On the upper end of this frame is threaded a T-shaped fitting 20 which is bound in position by nuts 21 and 22. The horizontally-extending neck portion of this fitting is greatly elongated to secure the threaded end of a laterally-extending arm 23, which arm is locked therein in adjusted position by a nut 24. On the outer end of the arm is mounted a bearing member 25 which is threaded at 26 to receive the threaded end of the arm 23 and this bearing is provided with a vertically-disposed hole 27 in which a spindle 28 is slidably mounted.

The lower end of this spindle is pointed as at 29 to fit into the central hole in the head of the valve 30 and the upper end of this spindle is threaded and screwed into the lower end or hub portion of the forked head 31, and between the arms 32 of this forked head is rotatably mounted a lifter pulley 33.

In order to lift the frame relatively to this spindle so as to compress the valve spring below, I have connected a flexible connector preferably in the shape of a

sprocket chain 34 at one end to the arm 23, and its opposite end is connected as at 36 to an opening in the pulley 33.

This pulley is fixed on a shaft 37, the 5 outer end 38 of which is squared, and on this squared portion is fixed a hub 39, the same being drilled and tapped as at 40 in several different places around its periphery to receive an operating 10 handle 41, whereby a downward swinging movement of this operating handle rotates the pulley to wind the chain upon its face thereby imparting a relatively lifting motion to the frame.

15 When the frame has been lifted so that its bearing member 25 abuts against the under shoulder of the spindle head, the valve spring 19 is compressed and as it is of importance to retain the spring in this compressed 20 position, I have mounted a pin 42 in the hub of the forked head and I may secure a flat spring detent 43 by means of screws 44 to the bearing member 25, which detent is provided with a hole 45 to receive 25 the pin 42 whereby an upward movement of this head causes the spring to engage and snap over the pin, and this spring is provided with a laterally-extending, operating arm 46 projecting into proximity to the operating lever 41, after the lever has been swung down to compress the valve spring 19, whereby a finger of the hand which engages the operating lever may be caused to bend the spring downwardly and withdraw it 30 from engagement with the pin 42 thereby releasing the head from the frame permitting relative movement between the two for the purpose of dropping the frame to release the valve spring 19.

35 In some instances, however, in the practical operation of the device, it is found necessary to swing the head on the axis of its spindle 28 to permit the operating handle 41 to clear some obstruction, and in order to 40 provide a dentent or lock which will retain the frame in raised position while the head is turned at an angle, I have constructed a 45 yoke-shaped latch 47 which is pivoted on its inturned ends 49 in the bearing 25, the bridge 50 of the yoke being on the arc of a 50 circle to fit about the hub of the head whereby it is adapted to engage the lock pin 42 even though the head is in a partially rotated position.

55 My improved valve compressing device is very simple and practical in construction and effective in its operation and is so designed that it may be quickly applied to an engine valve to compress the spring thereof 60 and be quickly removed for the purpose of permitting a grinding action upon the valve, and also the frame adjustments of the device permit it to be operated on engines of widely different types.

The foregoing description is directed solely towards the construction illustrated, but I desire it to be understood that I reserve the privilege of resorting to all the mechanical changes to which the device is susceptible, the invention being defined and limited only by the terms of the appended claims:

I claim:

1. A valve spring compressor comprising a frame having a presser foot-plate at its lower end shaped to straddle the valve stem and engaging the spring to be compressed, an upper laterally extending arm on said frame having a bearing, a spindle slideable in said bearing adapted to engage the top of the valve, a yoke on said spindle, a lever operated reel in said yoke, and a flexible connector attached to said reel to lift the frame and said spindle as the reel is rotated.

2. A valve spring compressor comprising a frame having a presser foot at its lower end and shaped to straddle the valve stem and engage the spring to be compressed, an upper laterally extending arm mounted to be vertically adjusted on said frame, a spindle vertically slideable in said arm, a pulley rotatably mounted on said spindle, a flexible connector leading from the arm to said pulley, a lever for rotating said pulley to wind the connector thereon and lift the frame and cause its bearing to slide on said spindle, and a latch for retaining the frame in adjusted position.

3. A valve spring compressor comprising a frame having a presser foot member at its lower end shaped to straddle the valve stem and engage the spring to be compressed, an upper laterally extending arm mounted to be vertically adjusted on said frame, a spindle vertically slideable in said arm, means including a lever for lifting the frame on said spindle and compress the spring below, and a latch for retaining the spindle in spring compressed position, said latch having its engaging portion formed on the arc of a circle to engage the locking member when said frame is in spring-compressed position even though the head is partially rotated on its axis.

4. A valve spring compressor comprising a frame formed of a rod having its lower portion inwardly offset and its end turned downwardly and connected to a T-shaped fitting, a presser foot having a threaded shank endwise adjustably mounted in said fitting, an upper endwise adjustable and laterally extending guide arm connected to the upper portion of said frame, a valve presser spindle in said arm, and means for imparting a relatively vertical movement to said frame and spindle to compress the spring.

5. A valve spring compressor comprising a frame having a presser foot member at its

lower end shaped to straddle the valve stem and engage the spring to be compressed, an upper laterally extending arm mounted to be vertically adjusted on said frame, a spindle vertically slidable in said arm, means including a lever for lifting the frame on said spindle and compress the spring below,

and means whereby said presser foot member and said upper arm may be adjusted to move the frame toward and from the spindle.

In testimony whereof I affix my signature.

WILLIAM C. BURROWS.
